UNITED STATES PATENT OFFICE.

HENRY B. KEIPER, OF LANCASTER, PENNSYLVANIA.

VALVE.

1,189,259.

Specification of Letters Patent.

Patented July 4, 1916.

Application filed May 15, 1914. Serial No. 838,736.

To all whom it may concern:

Be it known that I, HENRY B. KEIPER, a citizen of the United States, residing at Lancaster, in the county of Lancaster and State of Pennsylvania, have invented certain new and useful Improvements in Valves; and I hereby declare that the following is a full, clear, and exact description thereof, reference being had to the accompanying drawings, which form part of this specification.

This invention is a novel improvement in puppet valves, and its object is to provide a very quick-acting valve especially adapted for use with explosive engines where it is desirable to admit a charge of explosive gas practically altogether and instantaneously into the cylinder, instead of admitting it in a gradually increasing and then gradually decreasing flow; and to enable the exploded gases if desired to be practically bodily and instantaneously exhausted from the chamber.

The invention is also useful where it is desired to have a valve open fully and quickly and remain full open for a moment and then close quickly.

The essentially novel feature of the invention is having the valve and its seat move simultaneously and oppositely in opening and closing the valve, thus materially lessening the linear travel of the valve in fully opening or closing and effecting such full opening or closing very quickly.

I will more fully explain the invention as embodied in the puppet valves illustrated in the accompanying drawings, which show one practical use of the invention.

In said drawings: Figure 1 is a sectional elevation of two of my novel valves as applied to the cylinder of an explosive engine, showing one valve open, and the other closed. Fig. 2 is an enlarged sectional view on line 2—2 Fig. 1 showing the valve open; and Fig. 3 is a similar view showing the valve closed. Fig. 4 is a section on line 4—4. Fig. 1. Fig. 5 is a section on line 5—5, Fig. 1. Fig. 6 is a view similar to Fig. 1 but showing the inlet valve open and outlet valve closed, and also showing supplemental springs for returning the sleeve to normal position. Fig. 7 is a detail transverse sectional view on line 7—7 Fig. 6.

In the drawings E designates the cylinder of an engine of any suitable kind having a valve casing C secured to the cylinder head. Said cylinder and casing may be of

any desired kind and connected in any preferred way. The casing is shown as provided with two valves A, B, which are constructed as follows: The valve A preferably comprises a sleeve 1 which is slidably mounted within a suitable cylindric bore within the casing or casting C and is interposed between an inlet port c in said casting and a chamber or port e' leading to the working chamber of the engine. The sleeve 1 is open at its inner end but closed at its outer end and is provided with an opening 1^a in its side which registers with the port c as the sleeve is reciprocated. The sleeve is provided with a yoke 1^b on its outer end through which extends a cam shaft 2 suitably journaled in standards 7^a on a bar 7 attached to the casing C.

The inner end of the sleeve 1 is annularly beveled as at 1^c to form a seat for a puppet valve 3, which is adapted to fit the seat and is connected to a stem 3^a which extends through a suitable aperture in the outer end or head of the sleeve 1 and is held normally closed by means of a spring 4 interposed between the outer end of the sleeve 1 and a collar 3^b on the valve stem 3^a. The outer end of the stem 3^a may be guided in an opening in bar 7. The spring 4 keeps the valve 3 normally closed on the seat 1^c.

The shaft 2 is provided with a cam 2^b adapted to engage the end of the stem 3^a and unseat valve 3 by compressing the spring 4. Said shaft 2 is also provided with a cam 2^a adapted to engage the upper end of yoke 1^b and move the sleeve against the action of spring 4. The shaft 2 may be operated at the proper time to actuate the valve and sleeve by any suitable means; many such means are well known and will be readily supplied by the mechanician. The cams 2^a and 2^b are so formed and so located on shaft 2 that the sleeve 1 and valve 3 will be moved in opposite directions to open or close the valve, and thus the valve can be fully opened or closed very quickly. The stem 3^a should be so fitted to the aperture in the head of the sleeve that there will be no leakage of gas where the stem passes through the head of the sleeve. Means for preventing leakage at such points are well known and therefore need not be illustrated nor described.

While the spring 4 would normally tend to seat the sleeve and close the valve as indicated in Fig. 3, in some cases it may be de-

sired to supplement the action of the spring in returning the sleeve to normal position, and for this purpose additional springs may be used for seating the sleeve as indicated in Figs. 6 and 7; as shown in said figures a supplemental spring 8 is interposed between the top of the sleeve yoke 1^b and an arch bar 7^b attached to studs 7^a so that when the sleeve is raised both springs 4 and 8 will be tensioned and the sleeve will be returned to normal position, and held in normal position with greater pressure, than the puppet valve is held to its seat.

The outlet valve B is arranged beside valve A and is constructed like valve A, and similar parts thereof are similarly lettered.

It will be seen that the sleeve and puppet-valve move in different directions to open the valve, so that the opening for the passage of fluid is formed partly by the seat moving away from the valve, and partly by the valve moving away from the seat; and in this way the valve is fully opened in half the time, or just twice as fast as an ordinary puppet valve could be opened.

The full opening of the valve is obtained almost instantly by very slight opposite movements of both sleeve and valve thus providing a large opening for the passage of the gas or fluid, which can all pass practically instantly and uniformly, instead of being gradually allowed to flow past with increasing rapidity and then gradually choked off with increasing rapidity. By thus increasing the rapidity of opening of the puppet-valve more power can be obtained in the engine, owing to less back pressure; and more complete and instantaneous ignition is obtained.

The valve moves but about one-half the distance required to fully open it, and the seat moves the other half, the valve and seat moving oppositely and simultaneously when the shaft is turned, and both cams become operative.

In the construction illustrated the sleeve goes down and the puppet-valve goes up at the same time; and when they go as far as the cams permit the valve has opened as fully as an ordinary valve would open with twice the extent of movement, and such an ordinary valve would require twice the time. Practically, if the puppet-valves are the same diameter, the inlet valve A need not open as far as the outlet valve B, and in such case the cams for operating the outlet valve may be adapted to give a little more movement both to the valve and to its seat, at the opening of the valve so that there will be a larger opening for the escape of the exploded gases, thus preventing back pressure in the cylinder.

In Figs. 1, 2 and 3, the line *o* indicates the closed position of the valves; the line

v indicates the position of the valve when fully opened; and the line *s* the position of the seat when the valve is fully opened. The total opening of the valve is the distance between the lines *s* and *v*; but the valve only moves the distance between *o* and *s*,—(and the seat the distance between *o* and *v*)—in either the opening or closing of the valve. These valves open so quickly that practically the explosive gases will flow instantly into the cylinder, and the exploded gases escape instantly from the cylinder; this is a decided advantage as compared with the ordinary engines in which the valves open and close gradually and require approximately twice the time that my valves require for opening or closing; and therefore my valves can be made to stand fully open for at least half the time required for the opening and closing of an ordinary valve.

I have described and shown the valve and seat as moving uniformly in opposite directions to or from each other but by changing the cams the relative extent in time of movement of the cam and seat can be varied.

What I claim is:

1. In a valve, the combination of a seat, and a valve simultaneously movable in opposite directions to open or close the valve; and springs for closing the valve.

2. In a valve, the combination of a sleeve having a seat in one end, a valve adapted to fit said seat, a valve stem extending through the sleeve, means for simultaneously moving the valve and sleeve in opposite directions to open the valve; and a spring for closing the valve.

3. In a valve, the combination of a reciprocating sleeve having a valve seat, a reciprocating puppet valve adapted to engage said seat, a spring for moving the valve and sleeve in opposite directions to close the valve, and means for moving the sleeve and valve in opposite directions to open the valve.

4. In combination, a valve casing, a sleeve provided with a valve seat, a valve fitted to said seat, means adapted to simultaneously move the sleeve and valve in opposite directions, a spring for normally closing the valve on its seat, and a spring for returning the sleeve to normal position.

5. In a valve, the combination of a sleeve open at one end, a valve adapted to close the open end of the sleeve and having a stem extending through the opposite end of the sleeve, a collar on said stem, and a spring interposed between said collar and the sleeve to normally close the valve on the seat, and means for moving the valve and sleeve in opposite directions to open the valve.

6. In a valve, the combination of a casing having a port, a sleeve communicating with

said port and having a valve seat, a valve fitting the said seat and having a stem extending through the sleeve, a spring for closing the valve on its seat, and means for 5 simultaneously moving the valve and seat in opposite directions to open the valve.

7. In combination, a valve casing having a port, a sleeve communicating with said port having an open end provided with a 10 valve seat, a valve fitted to said seat and extending through the sleeve, a collar on said stem, a spring interposed between said collar and the sleeve, a shaft, cams on said shaft adapted to simultaneously move the sleeve and 15 valve in opposite directions to open the valve.

8. In combination, a valve casing having a port, a sleeve communicating with said port having an open end provided with a 20 valve seat, a puppet valve fitted to said seat and extending through the closed end of the sleeve, a collar on said stem, a spring interposed between said collar and the end of the sleeve, a yoke attached to the end of

the sleeve, a cam shaft extending through 25 said yoke, cams on said shaft adapted to simultaneously engage the yoke and stem to move the sleeve and valve in opposite directions, and a spring for returning the sleeve to normal position.

9. In a valve, the combination of a sleeve closed at one end, a valve adapted to close the open end of said sleeve and having a stem extending through the opposite end thereof, a lateral port in the wall of said 35 sleeve, means for moving the valve head away from said sleeve and for simultaneously moving said sleeve in a direction opposite and away from the direction of movement of said head.

In testimony that I claim the foregoing as my own, I affix my signature in presence of two witnesses.

HENRY B. KEIPER.
